SHIPPING CARTON

Clarence W. Vogt, Norwalk, Conn., assignor, by
mesne assignments, to Owens-Illinois Glass
Company, Toledo, Ohio, a corporation of Ohio

Application January 28, 1937, Serial No. 122,842
Renewed September 19, 1939

8 Claims. (Cl. 229—15)

The present invention relates to shipping cartons especially of the type adapted to contain flexible-walled packages.

Among the objects of the present invention is to provide a new and improved carton of the multiple cell type, which can be inexpensively manufactured, which can be easily and effectively folded from collapsed into package-receiving shipping condition, which is strong enough to effectively withstand ordinary handling during shipping, which is so constructed as to permit the ready insertion of empty flexible-walled containers through either end of said carton and into their respective cells for container-filling operations, which may be used to move said containers successively into filling position, and which permits the ready removal of the filled containers for dispensing from the latter.

Various other objects, features and advantages will be made apparent from the following particular description and from an inspection of the accompanying drawings. In these drawings:

Fig. 1 is a top plan view of the shipping carton with the bottom thereof closed.

Fig. 2 is a front elevation of the carton shown in Fig. 1 with a part broken away.

Fig. 3 is a section taken on the line 3—3 of Fig. 1.

Fig. 4 is a perspective of the carton in open position with the empty flexible-walled containers disposed in their respective cells, and in position to be filled.

Fig. 5 is a fragmentary perspective of the carton in shipping condition with the flexible-walled containers filled.

Fig. 6 is a section taken on line 6—6 of Fig. 5 but on an enlarged scale.

Fig. 7 is a perspective view of a form of flexible liquid container which may be stored or transported in the carton of the present invention.

Fig. 8 is a section taken on line 8—8 of Fig. 7 but showing the container partially collapsed, and

Fig. 9 is a section taken along the bottom seam of the container along the line 9—9 of Fig. 7.

In the specific forms illustrated the carton 10 is constructed from a blank which is made of comparatively rigid material such as double-faced corrugated cardboard, and which has a series of longitudinally extending score or crease lines along which the blank is folded to form a rectangular tube or casing having a pair of

comparatively wide opposed walls 11 and 12, and a pair of opposed narrower walls 13. Opposite edges of this blank may be secured together by any suitable means, as for instance, a tape 14 extending along one corner of the tubular 5 carton.

The top of the carton preferably has no closure, while the bottom thereof is provided with a closure flap 16 extending from, and foldable along the lower edge of the wall 11, and having 10 at its outer end a flap section 17 foldable outwardly with respect to the carton along a score or crease line 18. In closure position the main body of the flap 16 extends obliquely and upwardly from the lower edge of this wall 11 to the opposite wall 12 and the flap section 17 is lapped against said latter wall and secured thereto by fastening means which may be in the form of staples or wire stitches 20.

The lower ends of the carton walls 13 slant upwardly from the lower edge of the carton wall 11 in accordance with the inclination of the flap 16 in closed position, and are provided with flaps 21 adapted to overlie the bottom flap 16 when the latter is in closed position so that no gaps are formed along the lower corners of the carton, thereby eliminating the pinching of the flexible-walled packages at these corners.

The carton 10 is divided into a series of cells 22, four of such cells being shown. The partitions defining the carton cells 22 are easily and inexpensively formed by means of a partition member 23 which is made of suitable sheet material such as double-faced corrugated cardboard and which is folded into a series of rectangular U-shaped alternately reversed bends. In the specific form shown this member 23 comprises two adjacent bends 24 and 25 in reverse relationship having extensions 26 at their outer ends lapped against the carton walls 11 and 12 to form four cells of similar size and substantially square cross-section, and is secured in position in the carton 10 by adhesive or any suitable means throughout the entire areas of the transverse walls of the bends and the terminal end portions 26. The bottom of this partition member 23 preferably extends substantially at right-angles to the walls 11 and 12, as shown in Fig. 3, to form triangular openings 27 of substantial area between the bottoms of adjacent cells 22, thereby preventing the pinching of the flexible-walled packages at these sections.

The partition member 23 serves not only to divide the carton 10 into a series of cells, but

also serves to impart rigidity and strength to the carton.

Although the carton 10 has a variety of uses, it is particularly adapted to contain flexible-walled lubricant containers which may be drained into suitable receivers, such as crank cases of automobiles. In Figs. 7 to 9 is shown a form of flexible-walled oil bag or container 30 which may be conveniently and effectively packed in the carton 10, and which is more fully disclosed and claimed in a copending application, but it must be understood that any other type of flexible-walled container may be used for the purpose of the present invention.

10 This bag 30 is formed primarily of impervious flexible sheet material which may be sealed by heat and pressure, or by the use of adhesives or solvents. For instance, it may be material sold under the name of "Pliofilm", which is made from a chlorinated rubber compound, and which is thermoplastic and readily vulcanized or sealed at a temperature of approximately 115° C., so that overlapping sections thereof may be sealed together by the application of heat and pressure.

The bag 30 is formed of a sheet 31 of Pliofilm or other material referred to, having its side sections 32 heat-sealed to the sides of a narrower sheet of Pliofilm 33 along its entire length to form a tube. The sheet 31 is tucked inwardly from the sides of the sheet 33 to form a pair of in-folds 34 on each side of the collapsed tube.

Cemented or otherwise secured to the Pliofilm sheet 33 to form a laminated wall therewith, is a reenforcing sheet 35 made of paper or other flexible sheet material, which will not be injuriously affected by the application of sufficient heat and pressure to effect sealing, fusing or vulcanizing of the Pliofilm. In order that the corners of the bag 30 along the side edges of the sheet 35 be strong when the bag is filled, said sheet extends beyond the side edges of the Pliofilm sheet 33 to form marginal extensions 36, and portions of the side sections 32 of the Pliofilm sheet 31 project outwardly beyond the side edges of the sheet 33, and are directly glued or cemented to said marginal extensions.

The bottom of the bag 30 is closed by a seam 40 extending across the entire width of the bag 50 as shown in Figs. 7 and 9 and formed by heat-sealing the adjacent margins of Pliofilm together. At the top, the empty container is provided with side seals 41 in which the adjacent margins are heat-sealed together, the portion of the bag between said side seals forming a filling opening which may be permanently closed after the bag 55 is filled by heat-sealing the opposed Pliofilm linings of said opening together.

Since the sealing across the bottom of the collapsed tube is effected by a single heat-sealing operation, non-uniformity in the number of overlapping Pliofilms across the width of the collapsed tube might under some circumstances cause the overheating of the center portion of the tube, so that the overheated section of the Pliofilm sheet 31 along said center portion might stick to the platen member forming part of the sealing apparatus. In order to avoid this condition, a paper sheet 42 may be cemented or otherwise secured to the Pliofilm sheet 31 across an area extending slightly beyond the inner edges of the side seals 41.

The container 30 has a capacity which is greater than the amount of oil stored therein so as

to provide for the change in volume of oil due to changes in the temperature thereof.

The carton 10 without the partition member 23 may be shipped in flat, knocked-down condition to a remote station where the bags 30 are to be filled. The partition member may be previously secured in position and collapsed with the casing, or may be shipped separately. At this station the carton is set up in tubular form as shown in Fig. 4, and the partition member 23, if 10 shipped separately, is secured in position to divide the carton into the four rectangular cells 22. The set-up carton with its bottom flaps in open position are then passed underneath a filling apparatus. The empty collapsed bags 30 are inserted in 15 the individual cells 22, preferably from the lower end of the carton, with the upper ends thereof projecting beyond the upper end of the carton to render said bags readily accessible to the filling apparatus. The bags 30 are long enough so that 20 in the filling position the lower ends of said bags will project beyond the lower end of the carton. In this manner the expansion of the lower end of the bags during filling operations will be facilitated as there will be no folding over of the 25 bottoms of the collapsed bags before filling.

It is advantageous that the empty collapsed bags be inserted in their respective cells through the bottom of the carton so as not to interfere with the filling mechanism. Cooperating with this 30 filling mechanism is a series of bag-supporting fingers which grasp the upper end of the bag while the bags are being filled. Although the carton 10 in Fig. 4 is shown in an upright position, said carton is preferably inclined at an angle of approximately 45° during filling operation so as to reduce the amount of vertical space occupied by the carton during said operation and to minimize the strain on the bag-grasping fingers of the filling apparatus during said operation. 40 After the bags have been filled, a portion of the air may be exhausted from the head space above the liquid level, and the tops of the bags are hermetically heat-sealed between the side seals 41 by a sealing device constituting a heating member 45 adapted to act on one panel of the bag and cooperating with a platen member on the opposite panel of said bag, and preferably having a resilient face.

After the bags have been filled the side flaps 50 21 are folded inwardly and the bottom flap 16 is folded across the bottom of the carton in the position shown in Fig. 3. While in this closed position the staples 20 are applied at spaced sections to permanently secure the flap 16 in closed 55 position. As the main portion of the bottom 16 is above the lower edge of the wall 12 and flap 17, a certain resiliency is provided and there is less chance of rupturing the bags by dropping the carton or by other shocks or blows. After this 60 operation the upper ends of the filled bags are folded or will settle within the confines of the carton as shown in Fig. 5 to form a strong, compact, shippable unit in which these bags are effectively protected against injury during storage and transportation. Furthermore the construction of the carton is such that the staples 20 do not come in contact with the bags and therefore cannot injure said bags.

The cross-section of each carton cell is such 70 with respect to the cross-section of the filled bag therein to snugly hold said bag in said cell while permitting it to be pulled out of said cell with little effort. I have found, for instance, that with a filled quart bag of 10% to 11 inches perimeter,

a carton cell having an inside perimeter of $11\frac{1}{4}$ inches will be satisfactory and will create a very low initial drag or surface friction when said bag is withdrawn from the carton.

5 The complete unit as shown in Fig. 5 is particularly adapted to be used in the ordinary automobile service station since the oil bags are fully protected in the carton until they are dispensed, and may be easily pulled out of the carton when 10 it is desired to drain the contents of said bags into the crank case of an automobile.

When the carton is intended to hold only two bags the partition member may be dispensed with and the two bags made to mutually support 15 each other in the carton.

Having thus described my invention, what I claim as new and desire to secure by Letters Patent is:

1. A carton having a pair of similar opposed 20 substantially vertical walls with their lower ends in substantially the same plane at right-angles to the planes of said walls, said carton having a bottom integral with one of said walls and extending obliquely from the lower end thereof to 25 a point above the lower end of the opposed wall and secured to the latter.

2. A carton having a pair of similar opposed substantially vertical walls with their lower ends in substantially the same plane at right-angles 30 to the planes of said walls, said carton having a bottom integral with one of said walls and extending obliquely from the lower end thereof to a point above the lower end of the opposed wall and provided with a depending flap having its 35 lower edge substantially flush with the lower edge of the last-mentioned wall.

3. A carton having a pair of similar opposed substantially parallel and substantially vertical walls with their lower edges in the same plane, 40 whereby the carton may stand erect resting on said edges, and a bottom integral with one of said walls at the lower edge of the latter and extending upwardly across the carton and secured to the opposite wall at a point above the lower edge of the latter.

45 4. A carton having an inclined bottom wall and a plurality of partitions, said partitions terminating above the lower edge of said bottom wall, whereby the portions between said partitions are in open communication with each other at their lower ends.

5 A carton substantially rectangular in cross-section and having a pair of opposed substantially parallel walls having their lower edges in the same plane at right-angles to the planes of said walls, and a second pair of opposed walls having 5 their lower edges at an angle to said plane, and a bottom wall integral with one of said first-mentioned pair of walls and extending upwardly and inwardly to the other of said first-mentioned pair and substantially following the inclined lower edges of the walls of the second-mentioned pair.

6. A carton substantially rectangular in cross-section and having a pair of opposed substantially parallel walls having their lower edges in 15 the same plane at right-angles to the planes of said walls and a second pair of opposed walls having their lower edges at an angle to said plane, and a bottom wall integral with one of said first-mentioned pair of walls and extending 20 upwardly and inwardly to the other of said first-mentioned pair and substantially following the inclined lower edges of the walls of the second-mentioned pair, said second-mentioned pair of walls having flaps at their lower edges superposed 25 on said bottom wall.

7. A carton substantially rectangular in cross-section and having a pair of opposed substantially parallel walls having their lower edges in the same plane at right-angles to the planes of said 30 walls and a second pair of opposed walls having their lower edges at an angle to said plane, a bottom wall integral with one of said first-mentioned pair of walls and extending upwardly and inwardly to the other of said first-mentioned 35 pair and substantially following the inclined lower edges of the walls of the second-mentioned pair, and a plurality of partitions disposed between and parallel to said second pair of walls, and having their lower edges terminating above 40 the lower edge of said bottom wall.

8. A carton having an inclined bottom wall and a plurality of transverse partitions, each partition having one side edge terminating closely adjacent to the upper edge of said bottom wall, 45 and the opposite side edge terminating above the lower edge of said bottom wall, whereby the compartments between said partitions are in open communication with each other at their lower ends.

CLARENCE W. VOGT. 50
